EMERGENCY CONTROL APPARATUS FOR
RAILWAY SWITCHES

John R. Myers, New York, N. Y., assignor to Westinghouse Air Brake Company, a corporation of Pennsylvania

Application September 15, 1948, Serial No. 49,413

9 Claims. (Cl. 246—219)

1

My invention relates to railway switch controlling apparatus, and particularly to emergency control apparatus for at times effecting operation of any switch or pair of crossover switches selected from a given plurality of switches.

In power operated switch controlling apparatus such, for example, as that which may be embodied in interlocking control systems, the control circuits, which regularly effect operation of a switch between its normal and reverse positions, are commonly controlled in part by a relay which is known as a switch locking relay. The switch locking relay is in turn controlled in part by one or more traffic responsive relays so as to be normally energized, but to become deenergized in response to the presence of a train. In an emergency, it is sometimes desirable to effect operation of a track switch even though its switch locking relay is deenergized.

One feature of my invention is the provision of novel and improved group releasing means for effecting operation, in such an emergency, of any single switch or any pair of crossover switches selected from a given plurality of switches.

Another feature of my invention is the provision of means to prevent the releasing of any other single switch or any other pair of crossover switches at the same time that a selected single switch or a selected pair of crossover switches is released.

Still another feature of my invention is the provision of indication means for giving information to the leverman or the dispatcher concerning the condition of the emergency release apparatus and as to whether or not the emergency release procedure has been correctly initiated and may be completed.

I shall describe one form of apparatus embodying my invention, and shall then point out the novel features thereof in claims.

The accompanying drawings, Figs. 1a, 1b and 1c, when placed side by side, in the order named, with Fig. 1a on the left, constitute a diagrammatic view showing one form of apparatus embodying my invention, in which push-pull emergency release circuit controllers are used, for controlling a plurality of emergency release stick relays and a single time element device for controlling emergency control relays for arranging emergency control circuits for effecting operation of any selected single switch or pair of crossover switches in a plurality of railway track switches.

Referring to the drawings, a track plan is shown in Figs. 1b and 1c, in which two parallel tracks are interconnected by a crossover track, through

2

switches designated by the reference characters A1 and B1, and by a second crossover track, through switches designated by the reference characters A3 and B3. A single switch II is also shown, by which one of these two tracks is connected with an auxiliary track. In order to simplify the drawings, each track, comprising two parallel series of track rails, is represented by a single line.

10 Each of the tracks is divided into sections by insulated joints designated by the reference character 5. The section of track in which switches A1 and B3 are located is designated by the reference character A1T, the section in which switches B1 and A3 are located is designated by the reference character B1T, and the section in which switch II is located is designated by the reference character II T. Each of the sections A1T, B1T, and II T is provided with a track circuit including a suitable source of current, such as a battery 1, connected across the rails adjacent one end of the section, and a track relay designated by the reference character A1R, B1R, or II R, respectively, connected across the rails adjacent the opposite end of the section.

15 Traffic movements in opposite directions over sections A1T and B1T are governed by signals designated by the reference characters 2, 4, 6, and 8. Traffic movements in opposite directions over section II T are governed by signals designated by the reference characters 10, 12, and 14. The signals may be of any suitable design such, for example, as the searchlight type.

20 The contacts of the track relays are shown apart from the symbols for the relays by which they are operated. It is believed to be obvious that the contacts of each of the track relays are in the picked-up position when the associated track section is clear, and are in the deenergized position when the associated track section is occupied by a train.

25 Switches A1 and B1 are operated to their normal position, in which they are shown in the drawings, or to the opposite or reverse position, by mechanisms designated by the reference characters A1M and B1M, respectively. Mechanisms A1M and B1M are in turn controlled by a polarized switch control relay IW. Switches A3, B3, and II are similarly operated by mechanisms 30 designated by the reference characters A3M, B3M, and II M, respectively, which are in turn controlled similarly by polarized switch control relays 3W and II W, respectively.

35 Relay IW is regularly energized in the normal or in the reverse direction by circuits controlled

by a switch locking relay $1LS$ in the energized condition, and by a polarized lever repeater relay $1VP$, as well as by other means by which relay $1VP$ is also controlled, as will be referred to later. Relays $3W$ and $11W$ are also regularly energized in the normal or in the reverse direction by circuits controlled by switch locking relays $3LS$ and $11LS$, respectively, in the energized condition, and by a polarized lever repeater relay $3VP$ or $11VP$, respectively.

Relay $1LS$ has a pickup and a stick circuit controlled by the traffic responsive track relays $A1R$ and $B1R$, and by time locking stick relays associated with signals 2 , 4 , 6 , and 8 , respectively. The pickup circuit for relay $1LS$ is also controlled by a normally closed contact 21 of a manually operable switch control device $1V$, shown as a lever. Relay $3LS$ has a pickup and a stick circuit which are the same as the pickup and stick circuits for relay $1LS$ except that the pickup circuit includes contact 21 of a second manually operable switch control device, shown as a lever $3V$, instead of by lever $1V$, and the stick circuit for relay $3LS$ includes contact 22 of relay $3LS$ instead of contact 22 of relay $1LS$. Relay $11LS$ has a pickup and a stick circuit controlled by the traffic responsive track relay $11R$ and by time locking stick relays associated with signals 10 , 12 , and 14 , respectively. The pickup circuit for relay $11LS$ is also controlled by a normally closed contact 21 of a third manually operable switch control lever $11V$.

The time locking stick relays associated with signals 2 , 4 , 6 , 8 , 10 , 12 and 14 may be controlled, in accordance with conventional signal practice, similarly, for example, to the time locking stick relay Q^{S2} shown in the left-hand end of Fig. 1 of Letters Patent of the United States No. 2,211,523 granted August 13, 1940, to Lester E. Spray for Multiple Control Apparatus. As shown in that patent, each such time locking stick relay is controlled through the medium of a contact, designated by the reference character 36 , operated in conjunction with the associated signal so that the contact is closed only when the signal is indicating stop, and through a track relay such as relay T^s , and also through a time element device such as device N^{S2} . It is to be understood that the pickup circuits for the time locking stick relays associated with signals 2 and 6 will include contacts of relay $A1R$, the pickup circuits for the time locking stick relays associated with signals 4 and 8 will include contacts of relay $B1R$, and the pickup circuits for the time locking stick relays associated with signals 10 , 12 and 14 will include contacts of relay $11R$.

The conventional circuits for each of the time locking stick relays have been omitted in order to simplify the drawings. Contacts in Fig. 1a designated by the reference characters 15 and 55 are accompanied by a legend "Controlled by time locking stick relays associated with signals 2 , 4 , 6 and 8 ," meaning that each of these contacts is closed only when the time locking stick relays associated with signals 2 , 4 , 6 and 8 are all energized, and each of these contacts is open whenever any one of these time locking stick relays is deenergized. Similarly, contacts in Fig. 1c designated by the reference characters 15 and 55 are accompanied by a legend "Controlled by time locking stick relays associated with signals 10 , 12 and 14 ," meaning that each of these contacts is closed only when the time locking stick relays associated with signals 10 , 12 and 14 are all energized, and each of these contacts is open whenever any one of the time locking stick relays

associated with signals 10 , 12 and 14 is deenergized.

Relay $1VP$ is regularly controlled by relay $1LS$ and by lever $1V$, and may also be controlled by route control means shown conventionally as a manually operable lever $R1V$ having a center position c , and normal and reverse control positions n and r , respectively. Such route control means may, however, comprise route selector and exit stick relays such as those by which relay $1WR$ is shown controlled in Fig. 1C of Letters Patent of the United States No. 2,301,297, granted November 10, 1942, to Lloyd V. Lewis for Railway Traffic Controlling Apparatus. Relay $1W$ in Fig. 1a of applicant's drawings also may be controlled by the route control means shown for relay $1VP$. Relay $3VP$ is regularly controlled, similarly to relay $1VP$, by circuits which include contacts of relay $3LS$ and lever $3V$. Relay $11VP$ is also regularly controlled, similarly to relay $1VP$, by circuits including contacts of relay $11LS$ and lever $11V$.

The route control means by which relays $2VP$ and $3W$ are controlled is similarly shown conventionally as a manually operable lever $R3V$, and that by which relays $11VP$ and $11W$ are controlled is also shown conventionally as a manually operable lever $R11V$.

In apparatus embodying my invention, relays $1VP$ and $1W$ are also controlled, at times, by an emergency release stick relay $1ER$. Relays $3VP$ and $3W$ are also similarly controlled, at times, by an emergency release stick relay $3ER$, and relays $11VP$ and $11W$ are controlled, at times, by an emergency release stick relay $11ER$.

Lever $1V$ has a center position c , which it normally occupies, and has normal and reverse control positions n and r , respectively, to which it may be moved to effect operations of switches $A1$ and $B1$ to normal and reverse positions, respectively. Lever $1V$ has a latch contact 45 which is normally closed, but which opens during movement of lever $1V$ to its n or its r position, and which then again closes when lever $1V$ reaches the n or the r position. Each of the levers $3V$ and $11V$ has positions which are similar to those just described for lever $1V$, and each of the levers $3V$ and $11V$ has a latch contact 45 which is similar to latch contact 45 of lever $1V$.

Emergency release stick relay $1ER$ has a pickup circuit controlled by a manually operable emergency control device or release circuit controller, here shown as a push button $1PB$, as well as by time locking stick relays, and by back contacts of relay $1LS$, a time element device shown as a relay U , and a master release relay designated by the reference character ERP . Relay $1ER$ has also a stick circuit controlled by contact 45 of lever $1V$, by relay $1VP$, by normal and reverse switch indication relays $1NC$ and $1RC$, respectively, as well as by a back contact of relay $1LS$ and by time locking stick relays. Relays $3ER$ and $11ER$ are controlled similarly to relay $1ER$ as just described. A resistor t is connected in multiple with the winding of each of the relays $1ER$, $3ER$, and $11ER$ in order to make these relays slightly slow releasing. An asymmetric unit y , which may be of the well-known half-wave copper oxide rectifier type, is included in the pickup circuit for each of the relays $1ER$, $3ER$, and $11ER$ in order to protect these relays against operation by stray current.

Each of the push button circuit controllers $1PB$, $3PB$, and $11PB$ is of the push-pull type such, for example, as shown in Letters Patent of the

United States No. 2,295,301, granted September 8, 1942, to W. E. Smith for Circuit Controllers. Each of these controllers is biased to a normal or midstroke position, and has two normally open contacts 44 and 57. Each contact 44 becomes closed when its controller is pushed in, and each contact 57 becomes closed when its controller is pulled out.

A master release relay, designated by the reference character ERP, has three control circuits, each of which is controlled by a front contact of one of the relays 1ER, 3ER, and 11ER, and by back contacts of the other two of these relays.

An indication device, shown as a lamp, designated by the reference character ERK, is controlled by a front contact of relay ERP.

A time element device, shown as a relay U, is controlled in part by a front contact of relay ERP, and has three branch control paths, one of which includes contact 45 of lever IV, contact 57 of push button 1PB, and a front contact of relay 1ER. A second branch control path for relay U similarly includes contacts of lever 3V, push button 3PB, and relay 3ER, and a third branch control path also similarly includes contacts of lever 1V, push button 11PB, and relay 11ER.

An emergency control relay 1-3UP is controlled by circuits which include a front contact of time element device U, and a front contact of either of relays 1ER and 3ER, as well as the contacts in the circuits for time element device U. An emergency control relay 11UP is controlled by a circuit which includes the front contact of relay U, and a front contact of relay 11ER, as well as the contacts in the circuits for time element device U.

A polarized switch indication relay 1P is controlled similarly to relay h3 as shown in Fig. 1 of Letters Patent of the United States No. 2,211,522, granted August 13, 1940, to Lester E. Spray for Multiple Control Apparatus so as to be energized by current of normal polarity when switches A1 and B1 are in their normal positions, and to be energized by current of reverse polarity when switches A1 and B1 are in their reverse positions. Normal and reverse switch indication relays 1NC and 1RC, respectively, are controlled by relays 1P and 1W. A second polarized switch indication relay 3P is controlled, similarly to relay 1P, in conjunction with switches A3 and B3, and normal and reverse switch indication relays 3NC and 3RC are controlled similarly to relays 1NC and 1RC, by relays 3P and 3W. A third polarized switch indication relay 11P is controlled similarly to relay h4 as shown in Fig. 1 of the Spray Patent No. 2,211,522, and normal and reverse switch indication relays 11NC and 11RC are controlled similarly to relays 1NC and 1RC, respectively, by relays 11P and 11W.

Having described, in general, the arrangement and control of the apparatus shown by the accompanying drawings, I shall now describe, in detail, its operation.

As shown by the drawings, all parts are in their normal condition, that is, all switches are in their normal positions; all signals are indicating stop; track sections A1T, B1T, and 11T are unoccupied, and therefore track relays A1R, B1R, and 11R are energized; each of the levers IV, 3V, 11V, R1V, R3V, and R11V is in its center position c; each of the circuit controllers 1PB, 3PB, and 11PB is in its biased mid-stroke position; relays 1NC, 3NC, 11NC, 1LS, 3LS, 11LS, and the time locking stick relays associated with signals 2, 4, 6, 8, 10, 12 and 14 are energized; each of

the relays 1P, 3P, and 11P is energized by current of normal polarity; and time element device U, indication lamp ERK, and relays 1VP, 3VP, 11VP, 1W, 3W, 11W, 1RC, 3RC, 11RC, 1ER, 3ER, 11ER, ERP, 1-3UP, and 11UP are deenergized.

The pickup and stick circuits for switch locking relay 1LS are both closed. The pickup circuit passes from terminal B of a suitable source of current, such for example as a battery Q shown in Fig. 1a of the drawings, through contact 15 controlled by the time locking stick relays associated with signals 2, 4, 6 and 8, contacts 19 and 20 of relays B1R and A1R, respectively, winding of relay 1LS, and contact 21 of lever IV to terminal N of the same source of current. The stick circuit for relay 1LS is the same as its pickup circuit just traced through the winding of relay 1LS, and then passes through the front point of contact 22 of relay 1LS to terminal N. Pickup and stick circuits are also closed for relays 3LS and 11LS which are similar to the pickup and stick circuits just traced for relay 1LS.

The circuit by which relay 1NC is energized passes from terminal B, through contact 23 of relay 1P, contact 24 of relay 1P closed in the normal or left-hand position as shown in the drawing, winding of relay 1NC, and contact 25 of relay 1W closed in the normal position, to terminal N. Relays 3NC and 11NC are energized by similar circuits, shown in the drawings.

I shall first assume that a leverman or a dispatcher arranges for a train to pass signal 2, over switches A1 and B1 reversed, by moving route control lever R1V to its r position. Relay 1VP, therefore, becomes energized by its reverse control circuit passing from terminal B, through contact 26 of relay 1LS, right-hand portion of the winding of relay 1VP, contact 28 of lever R1V in the r position, and contact 30 of relay 1ER to terminal N. Relay 1W then becomes energized by its reverse control circuit passing from terminal B, through contact 31 of relay 1VP in its reverse position, front point of contact 32 of relay 1LS, winding of relay 1W, front point of contact 33 of relay 1LS, contact 34 of relay 1VP in its reverse or right-hand position, contact 28 of lever R1V in the r position, and contact 30 of relay 1ER to terminal N.

With relay 1W thus energized in the reverse direction, relay 1NC will be deenergized by the opening of contact 25 of relay 1W in its normal position, and mechanisms A1M and B1M will be energized, for moving switches A1 and B1 to their reverse positions, by circuits passing from terminal B, through contact 35 of relay 1W, contact 36 of relay 1W closed in the reverse or right-hand position, and mechanisms A1M and B1M, to terminal N.

Upon the completion of the operation of switches A1 and B1 to the reverse position, relay 1P will become energized in the reverse direction. Relay 1RC will then become energized by its circuit passing from terminal B, through contact 23 of relay 1P, contact 24 of relay 1P closed in the right-hand position, winding of relay 1RC, and contact 25 of relay 1W in its right-hand position, to terminal N.

Signal 2 will then be operated to the proceed position, causing the associated time locking stick relay to become deenergized. Relay 1LS will therefore become deenergized due to the opening of contact 15 which is controlled by the time locking stick relay associated with signal 2.

With relay 1LS deenergized, and relay 1P en-

ergized in the reverse direction, a reverse stick circuit for relay $1W$ will become closed, passing from terminal B, through contact 37 of relay $1W$ and contact 38 of relay $1P$, both closed in the right-hand or reverse position, back points of contacts 39 and 32 of relays $1ER$ and $1LS$, respectively, winding of relay $1W$, back points of contacts 33 and 40 of relays $1LS$ and $1ER$, respectively, and contact 41 of relay $1P$ closed in the reverse position, to terminal N.

I shall assume further that the leverman also arranges for the train to pass signal 10, over switch 11 reversed, by moving route control lever RIV to its r position. Relays $1VP$ and $1W$, switch 11 , relays $1P$ and $1RC$ and signal 10 will then become operated in the order named, similarly to the corresponding parts of the apparatus as previously described when the leverman arranges for a train to pass signal 2 over switches $A1$ and $B1$ reversed.

I shall now assume that all parts of the apparatus are again returned to the normal condition, and that relay $A1R$ becomes deenergized due to a failure in the track circuit for section $A1T$, such, for example, as due to a broken connection between the track battery 7 and the rails of the section. Contact 20 of relay $A1R$ will therefore be opened, causing relay $1LS$ to be deenergized.

I shall assume further that the leverman attempts to arrange for a train to move past signal 2 over switches $A1$ and $B1$ reversed, as before, by moving route control lever RIV to its r position. With relay $1LS$ deenergized, the circuit previously traced for relay $1VP$ is open at contact 26 of relay $1LS$, and hence relay $1VP$ cannot become energized by its regular reverse control circuit previously traced.

The leverman will therefore move lever IV to its r position, and will push circuit controller $1PB$ in to close its contact 44. Relay $1ER$ will therefore become energized by its pickup circuit passing from terminal B, through contacts 42 and 43 of relays U and ERP , respectively, contact 44 of push button $1PB$, asymmetric unit y , winding of relay $1ER$ in multiple with resistor t , contacts 50 and 51 of relays $1LS$ and $3NC$, respectively, and contact 55 which is controlled by the time locking stick relay associated with signal 2, to terminal N. Relay $1ER$, upon becoming energized, opens its back contact 30 in the regular control circuits previously traced for relays $1VP$ and $1W$, thereby preventing energization of these relays by their regular control circuits while the switches are under emergency control.

With relay $1ER$ energized, and with lever IV in its r position, relay $1VP$ will become energized by its emergency reverse control circuit passing from terminal B, through contact 27 of relay $1ER$, right-hand portion of the winding of relay $1VP$, and contact 21 of lever IV closed in the r position, to terminal N. Circuit controller $1PB$ may now be released to permit it to return to its mid-stroke position, because a stick circuit for relay $1ER$ will be closed, passing from terminal B, through contact 45 of lever IV , contact 46 of relay $1VP$ closed in the right-hand position, contact 47 of relay $1RC$, contact 49 of relay $1ER$, winding of relay $1ER$ in multiple with resistor t , contacts 50 and 51 of relays $1LS$ and $3NC$, respectively, and contact 55 which is controlled by the time locking stick relay associated with signal 2, to terminal N.

With relay $1ER$ energized, relay ERP will be energized by a circuit passing from terminal B,

through the front point of contact 65 of relay $1ER$, contacts 66 and 68 of relays $3ER$ and $11ER$, respectively, and the winding of relay ERP to terminal N. If the leverman should attempt to release switches $A3$ and $B3$ or switch 11 while he is releasing switches $A1$ and $B1$ by pushing circuit controller $3PB$ or $11PB$ in at the same time as controller $1PB$, the energization of relay $3ER$ or $11ER$ at the same time as relay $1ER$ would prevent energization of relay ERP because each of the control circuits for relay ERP includes back contacts of two of these relays. After relay ERP becomes energized in response to energization of one of the relays $1ER$, $3ER$ and $11ER$, contact 43 of relay ERP in the pickup circuits for these relays prevents energization of either of the other two of these relays.

With relay ERP energized, indication lamp ERK will be lighted by a circuit passing from terminal BX of a suitable source of lighting current, through contact 10 of relay ERP , and the filament of lamp ERK to terminal NX of the same source of lighting current. If lamp ERK remains constantly lighted, the leverman will know that the emergency release procedure has been correctly initiated, and that the apparatus is in condition for the emergency release procedure to be completed for effecting operations of switches $A1$ and $B1$ to their reverse positions. With lamp ERK constantly lighted, the leverman will then pull circuit controller $1PB$ out to close its contact 57 and thereby complete an energizing circuit for time element relay U , passing from terminal B, through contact 45 of lever IV , contact 46 of relay $1VP$ closed in the right-hand position, contact 47 of relay $1RC$, contact 56 of relay $1ER$, contact 57 of push button $1PB$, contact 58 of relay ERP , and the winding of relay U to terminal N. Upon the lapse of a measured period of time, time element relay U closes its contact 59, thereby completing a circuit for energizing relay $1-3UP$, which is the same as the circuit previously traced for relay U as far as contact 58 of relay ERP , and thence passing through contact 59 of relay U , contact 60 of relay $1ER$, and the winding of relay $1-3UP$ to terminal N. It is necessary for the leverman to hold controller $1PB$ in the pulled-out position until time element relay U has had time to close its contact 59 for energizing relay $1-3UP$ and effecting operation of the contacts of relay $1W$ to their reverse positions.

With relay $1VP$ energized by current of reverse polarity, and with relay $1-3UP$ energized, the reverse control circuit for relay $1W$ will be closed passing from terminal B, through contact 31 of relay $1VP$ closed in the reverse or right-hand position, contact 63 of relay $1-3UP$, front point of contact 39 of relay $1ER$, back point of contact 32 of relay $1LS$, winding of relay $1W$, back point of contact 33 of relay $1LS$, front point of contact 40 of relay $1ER$, contact 64 of relay $1-3UP$, contact 34 of relay $1VP$ in the reverse or right-hand position, and contact 21 of lever IV closed in its r position, to terminal N.

With relay $1W$ thus energized by current of reverse polarity, mechanisms $A1M$ and $B1M$ will become energized for operating switches $A1$ and $B1$ to their reverse positions, as previously described. Relay $1P$ will then become energized in the reverse direction, and relay $1RC$ will become energized as previously described. Relay $1RC$, upon becoming energized, opens its back contact 47, thereby breaking the stick circuit

previously traced for relay IIER and causing relay IIER to become deenergized.

I shall next assume that relay IIIR becomes deenergized due to a failure in the track circuit for section IIIT . Contact 20 of relay IIIR will therefore be opened, causing relay IIILS to be deenergized.

I shall assume further that the leverman attempts to arrange for a train to move past signal I0 , over switch II reversed, by moving route control lever RIV to its r position. With relay IIILS deenergized, the circuit for relay IIIVP which includes contact 26 of relay IIILS will be open, and hence relay IIIVP cannot become energized by its regular reverse control circuit.

The leverman will therefore move lever IIIV to its r position and will push circuit controller IIIPB in to close its contact 44 . Relay IIER will therefore become energized by its pickup circuit passing from terminal B , through contacts 42 and 43 of relays U and ERP , respectively, contact 44 of push button IIIPB , asymmetric unit y , winding of relay IIER in multiple with a resistor t , contact 50 of relay IIILS , and contact 55 which is controlled by the time locking stick relay associated with signal I0 , to terminal N . Relay IIER , upon becoming energized, opens its back contact 30 in the regular control circuits for relays IIIVP and IIW , thereby preventing energization of these relays by their regular control circuits while the switch is under emergency control.

With relay IIER energized, and with lever IIIV in its r position, relay IIIVP will become energized by its emergency reverse control circuit passing from terminal B , through contact 27 of relay IIER , right-hand portion of the winding of relay IIIVP , and contact 21 of lever IIIV closed in its r position, to terminal N . Circuit controller IIIPB may now be released to permit its return to its mid-stroke position because a stick circuit for relay IIER will be closed, passing from terminal B , through contact 45 of lever IIIV , contact 46 of relay IIIVP closed in the reverse or right-hand position, as shown in the drawing, contact 47 of relay IIIRC , contact 49 of relay IIER , winding of relay IIER in multiple with a resistor t , contact 50 of relay IIILS , and contact 55 which is controlled by the time locking stick relay associated with signal I0 , to terminal N .

With relay IIER energized, relay ERP will be energized by a second circuit, passing from terminal B , through the back point of contact 65 of relay IIER , back point of contact 67 of relay IIER , contact 69 of relay IIER , and the winding of relay ERP to terminal N .

The leverman will then pull circuit controller IIIPB out to close its contact 51 , and thereby complete an energizing circuit for time element device or relay U , passing from terminal B , through contact 45 of lever IIIV , contact 46 of relay IIIVP closed in its reverse position, contact 47 of relay IIIRC , contact 56 of relay IIER , contact 57 of push button IIIPB , contact 58 of relay ERP , and the winding of time element device U to terminal N . It will be necessary for the leverman to hold controller IIIPB in this position until time element relay U has had time to close its contact 59 and effect energization of relay IIW by completing a circuit for energizing relay IIUP which is the same as the circuit just traced for time element relay U as far as contact 58 of relay ERP , and then including contact 59 of relay U , contact 62 of relay IIER , and

the winding of relay IIUP to terminal N . With relay IIUP energized, a reverse emergency control circuit will be completed for relay IIW , passing from terminal B , through contact 31 of relay IIVP in its reverse position, contact 63 of relay IIUP , front point of contact 39 of relay IIER , back point of contact 32 of relay IIILS , winding of relay IIW , back point of contact 33 of relay IIILS , front point of contact 40 of relay IIER , contact 64 of relay IIUP , contact 34 of relay IIVP closed in the reverse position, and contact 21 of lever IIIV closed in its r position, to terminal N .

With relay IIW thus energized by current of reverse polarity, mechanism IM will be energized for operating switch II to its reverse position. Relay IIIP will then become energized in the reverse direction, and relay IIIRC will become energized as previously described. Relay IIIRC , upon becoming energized, opens its back contact 47 , thereby breaking the stick circuit previously traced for relay IIER , and causing relay IIER to become deenergized.

With relay IIER deenergized, relay ERP will be deenergized, causing lamp ERK to be extinguished. Relays U and IIUP will also be deenergized.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In railway switch controlling apparatus for a plurality of railway track switches including regular control means for each of said switches for effecting operations of the corresponding switch to normal and reverse positions only if a corresponding switch locking relay controlled by traffic responsive means is energized, including a plurality of manually controllable railway switch control devices one for each of said switches each having normal and reverse control positions for controlling operations of its switch to normal and reverse positions respectively, the combination comprising, a plurality of emergency release stick relays one for each of said switches, a time element device, a master release relay, a manually controllable pickup circuit for each of said release stick relays for energizing its release stick relay if the corresponding switch locking relay and said time element device and said master release relay are all deenergized, a stick circuit for each of said release stick relays for retaining its release stick relay energized as long as the corresponding switch locking relay is deenergized and the corresponding switch control device remains in one of its control positions, a plurality of energizing circuits for said master release relay one for each of said release stick relays each controlled by a front contact of its release stick relay and by a back contact of each of the other release stick relays, means controlled by said master release relay for energizing said time element device, and emergency control means controlled by said time element device and by each of said release stick relays for effecting operations of each associated switch while the associated switch locking relay is deenergized.
2. In railway switch controlling apparatus including regular control means for each of a

plurality of switches for effecting operations of the corresponding switches to normal and reverse positions, the combination comprising, an emergency release stick relay for each of said switches, an emergency control device for each of said switches each biased to a normal position but manually operable to a first and a second control position, a pickup and a stick circuit for each of said release stick relays for energizing the corresponding release stick relay under a given traffic condition which prevents the associated regular control means from effecting operations of the associated switch and each of said pickup circuits also controlled by the corresponding emergency control device in its first control position, a time element device controlled by a plurality of circuits one for each of said switches each controlled by the corresponding emergency control device in its second control position, and emergency control means for each of said switches controlled by a front contact of the said release stick relay for the corresponding switch and by said time element device for effecting operations of the said corresponding switch.

3. In railway switch controlling apparatus including regular control means for each of a plurality of switches for effecting operations of the corresponding switches to normal and reverse positions, the combination comprising, an emergency release stick relay for each of said switches, an emergency control device for each of said switches each biased to a normal position but manually operable to a first and a second control position, a master release relay, a pickup and a stick circuit for each of said release stick relays for energizing the corresponding release stick relay under a given traffic condition which prevents the associated regular control means from effecting operations of the associated switch and each of said pickup circuits also controlled by the corresponding emergency control device in its first control position and by a back contact of said master release relay, a plurality of energizing circuits for said master release relay one for each of said release stick relays each controlled by a front contact of its release stick relay and by a back contact of each of the other release stick relays, and emergency control means for each of said switches controlled by the corresponding emergency control device in its second control position and by the corresponding release stick relay and also by said master release relay.

4. In railway switch controlling apparatus including regular control means for each of a plurality of switches for effecting operations of the corresponding switches to normal and reverse positions, the combination comprising, an emergency release stick relay for each of said switches, an emergency control device for each of said switches each manually operable to a first and a second control position, a master release relay, means controlled by each of said emergency control devices in its said first control position while said master release relay is deenergized for effecting energization of the corresponding release stick relay under a given traffic condition which prevents the associated regular control means from effecting operations of the associated switch, stick circuit means for then retaining the corresponding release stick relay energized under said given traffic condition, means controlled by each of said release stick relays in its energized condition while each

of the other release stick relays is deenergized for energizing said master release relay, and emergency control means for each of said switches controlled by the corresponding emergency control device in its second control position and by said master release relay.

5. In railway switch controlling apparatus including regular control means for each of a plurality of switches for effecting operations of the corresponding switches to normal and reverse positions, the combination comprising, an emergency release stick relay for each of said switches, an emergency control device for each of said switches each manually operable to a first and a second control position, means including each of said emergency control devices in its said first control position for effecting energization of the corresponding said release stick relay under a given traffic condition which prevents the associated regular control means from effecting operations of the associated switch, stick circuit means for then retaining the corresponding release stick relay energized under said given traffic condition, and emergency control means for each of said switches controlled by the corresponding emergency control device in its said second control position and by the corresponding release stick relay in its energized condition while each of the other release stick relays is in its deenergized condition.

6. In railway switch controlling apparatus including regular control means for each of a plurality of switches for effecting operations of the corresponding switches to normal and reverse positions, the combination comprising, an emergency release stick relay for each of said switches, an emergency control device for each of said switches each manually operable to a first and a second control position, means including each of said emergency control devices in its said first control position for effecting energization of the corresponding said release stick relay under a given traffic condition which prevents the associated regular control means from effecting operations of the associated switch, stick circuit means for then retaining the corresponding release stick relay energized under said given traffic condition, an indication device, means controlled by each of said release stick relays in its energized condition while each of the other release stick relays is deenergized for energizing said indication device, and emergency control means for each of said switches controlled by the corresponding emergency control device in its said second control position and by a front contact of the corresponding release stick relay.

7. In railway switch controlling apparatus including regular control means for each of a plurality of switches for effecting operations of the corresponding switches to normal and reverse positions, the combination comprising, an emergency release stick relay for each of said switches, an emergency control device for each of said switches each manually operable to a first and a second control position, a time element device, means including a back contact of said time element device and including each of said emergency control devices in its said first control position for effecting energization of the corresponding release stick relay under a given traffic condition which prevents the associated regular control means from effecting operations of the associated switch, stick circuit means for

then retaining the corresponding release stick relay energized under said given traffic condition, means controlled by each of said emergency control devices in its said second control position and by the associated release stick relay in its energized condition while the other release stick relays are deenergized for energizing said time element device, and emergency control means for each of said switches controlled by the associated release stick relay and by a front contact of said time element device.

8. In railway switch controlling apparatus for a plurality of railway track switches including regular control means for each of said switches for effecting operations of the corresponding switch to normal and reverse positions only if a corresponding switch locking relay controlled by traffic responsive means is energized, the combination comprising, a manually controllable release relay for each crossover pair of said switches and for each other switch, and emergency control means for each of said crossover pairs of switches and for each other switch controlled by a front contact of the associated release relay and by back contacts of all the other release relays for effecting operations of each corresponding switch to normal and reverse positions if the corresponding switch locking relay is deenergized.

9. In railway switch controlling apparatus for a plurality of railway track switches including regular control means for each crossover pair of said switches and for each other switch for effecting operations of each corresponding

switch to normal and reverse positions only if a corresponding switch locking relay controlled by traffic conditions is energized, the combination comprising, a manually controllable release relay for each crossover pair of said switches and also for each other switch, an indication device, means controlled by a front contact of each of said release relays while all the other said release relays are deenergized for energizing said indication device, and emergency control means for each of said crossover pairs of switches and for each other switch controlled by a front contact of the associated release relay and by back contacts of all the other release relays for effecting operations of each corresponding switch to normal and reverse positions if the corresponding switch locking relay is deenergized.
